LOW-FREQUENCY CORRECTION OF IMAGE AMPLIFIERS

Kurt Schlesinger, Berlin, Germany, assignor, by
mesne assignments, to Loewe Radio, Inc., a cor-
poration of New York

Application November 9, 1937, Serial No. 173,695
In Germany November 14, 1936

3 Claims. (Cl. 179—171)

The present invention relates to television receivers and more particularly to video signal amplifiers the anode current of which is taken from a storage condenser charged by a rectifier via a steadyng resistance.

It is known that in this case amplifiers with R. C.-coupling exhibit an increased amplification of low frequencies. This effect has even been utilised sometimes for compensating the drop in amplification of low frequencies otherwise caused by capacitative coupling. The applicant has found, however, that in the case of correctly dimensioned condenser coupling there is no difficulty in the transmission of the low video frequencies, but that the said increase in amplification owing to the steadyng circuit leads to troublesome interferences. The amplifier gets super-sensitive in respect of frequencies below 50 cycles and responds to very small impulses, for example to disturbances coming from the mains, whereby there is caused a continuous flashing of the light intensity of the image. A more serious fault is that the described fault leads to detrimental image distortions, viz., to incorrect light intensity values over large areas of the image, which is explained more concisely later on. The increase in amplification takes place in each single stage of the amplifier, and these errors are cumulative. The applicant has recognized that these disturbances arising in television may be compensated by use of a special circuit-system arranged in the cathode line of the R. C.-coupled amplifier so that the anode current is passing through this special circuit, consisting of a parallel connection of a resistance and a condenser.

Further objects of the invention may be best understood by reference to the following description taken in connection with the accompanying drawing, in which

Figs. 1 and 6 are diagrams showing the connection of an amplifier according to the invention, whilst

Figs. 2 to 5 are graphs of grid and anode voltages.

Fig. 1 shows an amplifying stage consisting of a pentode 15 with anode potential source (mains supply) 8, steadyng means (resistance 2 and storage condenser 3) and anode resistance 1. The input potential source 4 is coupled to the grid of the pentode via condenser 5 and resistance 12. The output device 6 is connected to the anode via a coupling condenser 7.

In the following the resistance 1 is designated R_1 , the capacity of condenser 3 C_3 ; V is the am-

plification factor, S the steepness of the characteristic of the pentode.

Upon considering Fig. 1 it will be clear that if the correcting circuit 9/10 according to the invention is missing the condenser 3 no longer performs short-circuiting, so that in respect of very low frequencies the total of the resistances 1 and 2 acts as coupling resistance, so that the amplification increases from $V_1 = S \cdot R_1$ to $V_2 = (R_1 + R_2)$.
10 The rate at which this increase takes place possesses the time constant $T_3 = C_3 \cdot R_2$.

If at 4 a potential e_g of rectangular form (Fig. 2) is applied to the grid a potential e_a (Fig. 3) is obtained at 6, the values 21 and 22 corresponding 15 to the amplification factors V_1 and V_2 .

The applicant has found that it is possible to eliminate this distortion by inserting in the lead to the cathode a correcting circuit, which consists of condenser 9 shunted by resistance 10.

20 The emission current forms after some time at the cathode a bias $S \cdot R_{10} \cdot e_g$ which is subtracted from the input potential e_g at 4. The result is a corrective effective grid control potential e_c as shown in Fig. 4 which drops in such fashion that 25 the desired correct anode potential wave e_a according to Fig. 5 is obtained as a result of the two effects in the cathode and anode circuits.

The theoretical calculation results in the values:

$$30 \quad R_{10} = \frac{R_2}{V_1}$$
$$C_9 = C_3 \cdot V_1$$

It is presumed the resistance 10 is negligible in 35 comparison to resistances 1 and 2.

Example.—The filtering may necessitate $C_3 = 20$ mfd., $R_2 = 300$ ohms. Steepness of the tube 2 mA/V, $R_1 = 1,000$ ohms, consequently $V_1 = 2$. From this there is to be calculated $R_{10} = 150$ ohms,

40 $C_9 = 40$ mfd. C_9 may be an electrolytic condenser.

It is to be recognised that the dimensions of circuit 9—10 depend only on those of 2—3, without consideration of the static working conditions, i. e. the bias occurring across resistance 10 under the effect of the normal anode current. It may accordingly occur that the tube having this bias determined by R_{10} does not operate satisfactorily. In this case an additional bias 11 must be supplied to the grid by way of the high resistance 12.

45 It has been found, however, that a still better correction is obtained by a connection according to Fig. 6. A resistance 16 is put in series to condenser 9 and, in order to obtain sufficient earth-
50 ing of the cathode for high and medium fre-

quencies an additional condenser 17 is provided in parallel to both. The proper value of resistance 16 is preferably ascertained by oscillographic observation of the output potential e_a at 6 which is obtained from a rectangular grid input potential e_g of approximately 25 cycles. Consideration shows that the filter condenser 3 is dynamically charged by the series resistance 1 and thus effects a phase difference, whilst the condenser 9 if 16 is not provided is directly fed by 10 anode current.

Values ascertained in practice in respect of a correcting circuit are, for example, the following:

$$\begin{aligned}C_9 &= 40 \text{ mf.}, \\R_{16} &= 200 \text{ ohms}, \\R_{10} &= 5000 \text{ ohms}, \\C_{17} &= 10^{-5} \text{ mf.},\end{aligned}$$

and, for a twofold amplification:

$$\begin{aligned}R_1 &= 1,000 \text{ ohms}, \\R_2 &= 10,000 \text{ ohms}, \\C_3 &= 20 \text{ mf.}\end{aligned}$$

It is clear that as many stages of this kind as desired, corrected with respect to the rectangular wave, can be connected in cascade, and that a multistage image amplifier is then also corrected in its entirety. A condition in this connection is that the coupling elements 5/12 transmit the low tones in question without drop. For television purposes this condition even in the case of 25 image changes is completely fulfilled if for example $C_5=0.5$ mf., $R_{12}=0.3$ megohms.

I claim:

1. A resistance-capacity coupled amplifier arrangement for television purposes comprising an amplifier tube having at least a cathode, anode and control grid, an input and output circuit, a power supply circuit, an anode-resistance and steadyng means consisting of a steadyng condenser and a steadyng resistance in said output circuit, a compensating circuit connection for compensating the increase in amplification of the low frequencies effected by said steadyng means, said compensating circuit connection being arranged within the cathode line of said tube carrying the anode current and consisting of a correcting resistance to which on the one side a correcting condenser with a serially connected resistance and on the other side a shunting condenser is connected in parallel, said correcting resistance having a resistance value amounting

5 to R/V , said first correcting condenser having a value amounting to C times V , R being the steadyng resistance, V being the normal amplification and C being the steadyng condenser, said shunting condenser being so dimensioned as to short-circuit the middle and high frequencies.

2. A resistance capacity coupled amplifier circuit arrangement for television purposes consisting of a plurality of single amplifier stages, each of said stages comprising an amplifier tube having at least a cathode, anode and control grid, an input and output circuit, a power supply circuit, an anode-resistance and steadyng means consisting of a steadyng condenser and a steadyng

15 resistance in said output circuit, a compensating circuit connection for compensating the increase in amplification of the low frequencies effected by said steadyng means, said compensating circuit connection being arranged within the cathode line of said tube carrying the anode current and consisting of a correcting resistance to which on the one side a correcting condenser with a serially connected resistance and on the other side a shunting condenser is connected in parallel, said

20 correcting resistance having a resistance value amounting to R/V , said correcting condenser having a value amounting to C times V , R being the steadyng resistance, V being the normal amplification and C being the steadyng condenser, said shunting condenser being so dimensioned as to short-circuit the middle and high frequencies.

25 3. In a wide band amplifier, a thermionic tube, having at least a cathode, a control electrode, and an output electrode, means to apply input signals 35 between the control electrode and a predetermined point of fixed potential, means including a serially connected load impedance and a decoupling resistor connected to the output electrode for maintaining the output electrode positive relative to said point of fixed potential, a decoupling condenser connected between the junction of said load impedance and the decoupling resistor and the point of fixed potential, and a parallelly connected condenser and resistor connected between the cathode and the said point of fixed potential, said last named parallelly connected resistor and condenser having a time constant substantially equal to that of the decoupling resistor and condenser, whereby low frequency components of applied signals are undistortedly amplified.

KURT SCHLESINGER.
